UNITED STATES PATENT OFFICE.

BERNARD H. HILMES, OF ALTAMONT, ILLINOIS.

SCREW-CUTTING DIE AND HOLDER.

SPECIFICATION forming part of Letters Patent No. 240,709, dated April 26, 1881.

Application filed February 18, 1881. (No model.)

To all whom it may concern:

Be it known that I, BERNARD H. HILMES, of Altamont, in the county of Effingham and State of Illinois, have invented a new and useful Improvement in Screw-Cutting Dies and Holders, of which the following is a specification.

The object of my invention is a screw-cutting machine or implement the dies of which shall be reversible and so held and operated that after the formation of the thread the bolt may be removed from between the dies without the necessity of unscrewing the bolt or turning the machine back.

15 In the accompanying drawings, Figure 1 is a front elevation of my invention. Fig. 2 is a side view with a portion of the head and shank cut away, and Fig. 3 is a longitudinal section taken on the line $\alpha\alpha$ of Fig. 1.

20 Similar letters of reference indicate corresponding parts.

A represents the enlarged circular head, and A' the shank, of the hollow cast-metal die-holder.

25 The ring B, which fits the periphery of the head A, is chambered out, as shown at b, and provided in a diametrical line with the square-headed screw-bolts a a, which pass through the ring, and the inner ends of which are rounded, 30 as shown, to act as cams. This ring is also provided with the screw-bolts c c, the inner ends of which are pointed and have a limited movement in the shallow grooves e e in the periphery of the circular head, which grooves have 35 the stops e' e' for limiting the movement of the ring around the head.

The front face of the head is formed with the dovetailed or undercut slot or groove C, in which the dies D D are held, and the head is 40 also provided with the openings E E, through which the ends of the springs F F pass. The springs F F are secured to the ring G, which surrounds the shank of the holder, by the screws f f, and the ring is secured to the shank 45 and is adjustable thereon by means of the set-screw g. The dies D D, of the width and length to correspond with the width and length of the groove in the face of the holder and with

the central opening thereof, are each formed with the thread-cutters d d' for different sizes 50 of bolts and threads, and with the beveled edges i i to correspond with the undercut slot in the face of the head, and the corners h h of the dies are rounded, as shown, to act as cams in connection with the bolts a a, and the recesses j are formed in their under sides to engage with the ends of the springs F F. 55

In operation the dies are brought to position and held for cutting the thread by turning the ring B upon the head of the die-holder, the screws a a having been first adjusted so that the inner rounded ends thereof, coming in contact with the rounded corners of the dies, will force the dies the proper distance toward each other. The thread having been formed by 60 turning either the holder or the bolt by hand or mechanical power, the ring B is to be turned in a direction opposite to that first named, thus permitting the dies to be thrown back by the springs F F, whereby the bolt is released 65 without the necessity and trouble of unscrewing the same, as heretofore. 70

The dies may be removed from the holder and reversed by simply removing the ring B by unscrewing the bolts c c and moving back 75 upon the shank the collar G, thus carrying the ends of the springs out of the recesses in the dies.

Having thus fully described my invention, I claim as new and desire to secure by Letters 80 Patent—

1. In a screw-cutting die and holder, the screw-bolts a a, provided with end cams passing through the ring B and acting against spring-retracted dies, as shown and described. 85

2. The dies D D, formed with the beveled edges i i and with the rounded corners h h, and having the recesses j j in their under side, in combination with the ring, having the set-screw g, and with the springs F F, substantially as and for the purposes shown and described. 90

BERNARD HERMANN HILMES.
